Robert H. Young
Attorney

UNITED STATES PATENT OFFICE.

HARRY C. CRAY, OF DAYTON, OHIO.

WATER BALLAST FOR BALLOONS.

Application filed May 29, 1923. Serial No. 642,257.

To all whom it may concern:

Be it known that I, HARRY C. CRAY, a citizen of the United States, residing at Dayton, in the county of Montgomery and State of Ohio, have invented certain new and useful Improvements in Water Ballast for Balloons, of which the following is a specification.

This invention relates in general to ballast devices for spherical observation balloons and more particularly to an observation basket of the type used on such aircraft which is provided with a water tank within its walls adapted to carry a sufficient supply of water or other suitable fluid to act as a ballast for the craft.

It is the object of my invention to equip observation or spherical balloons with an observation basket having a fluid tank built into its walls, and providing this tank with a suitable control for releasing the fluid ballast as required.

The figure is a perspective view of my device with portions broken away for purpose of better disclosure.

The basket 3 is secured to the balloon or

similar aircraft by means of rigging 2, suitable securing means being provided at 6. This basket is provided with a double wall to include a suitable fluid ballast tank 4. A 30 control lever 5 operating a suitable outlet valve 8 is provided to permit the release of the fuel ballast as desired through the outlet tube 7.

When it is desired to release ballast it is 35 merely necessary to turn the ballast control lever 5 to open the valve and permit the escape of the amount of ballast desired.

Claims:

1. An observation basket for balloons and 40 the like having the upright walls thereof comprised of spaced partitions to provide a ballast tank, and valve means associated with the tank.

2. An observation basket for balloons and 45 the like having a ballast tank built into the upright walls thereof, valve means in said tank, and valve controlling means extending through the upper edge of one of said walls.

In testimony whereof I affix my signature,

HARRY C. CRAY.
